UNITED STATES PATENT OFFICE.

CLEVELAND SIMPSON, OF WINSTON-SALEM, NORTH CAROLINA, ASSIGNOR OF ONE-HALF
TO JOHN L. BERRIER, OF WINSTON-SALEM, NORTH CAROLINA.

PHOTOGRAPHIC-PRINTING MACHINE.

Application filed March 8, 1920. Serial No. 364,566.

To all whom it may concern:

Be it known that I, CLEVELAND SIMPSON, a citizen of the United States, residing at Winston-Salem, in the county of Forsyth and State of North Carolina, have invented a new and useful Photographic-Printing Machine, of which the following is a specification.

This invention has reference to photographic printing machines whereby photographic prints may be produced from negatives with rapidity and without the necessity of handling the photographic paper after exposure to actinic light passing through the negative.

In accordance with the invention, there is provided a box of appropriate size and form, housing a light giving unit or units from which light may be transmitted through a negative to affect a sensitized sheet held against the negative, in the usual manner.

Provision is made for positioning the sensitized paper and for numbering such paper, and, at the same time, manipulating a presser board for the negative and paper, and for causing the paper, after being light printed, to leave the negative and gravitate to a protected position, the operation of the structure being in a manner to facilitate the production of the light prints.

The invention will be best understood from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient features of the invention as expressed in the appended claims.

In the drawings,

Fig. 1 is a perspective view of a photographic printing machine embodying the invention and showing the presser board in the open position.

Fig. 2 is a front elevation with some parts in section of the structure shown in Fig. 1.

Fig. 3 is a plan view of a portion of the structure shown in Fig. 1, with a portion of the casing in horizontal section.

Fig. 4 is a section on the line 4—4 of Fig. 2.

Fig. 5 is a perspective view of a tiltable or rockable print carrying shelf forming part of the invention.

Fig. 6 is a perspective view of a clamp for holding the negative and also utilizable as part of a mat.

Referring to the drawings, there is shown a table 1 which may also be taken as typical of a bench or other support, and it is to be understood that the table 1 may be carried upon legs 2 or may be otherwise mounted.

On the top of the table 1, there is secured a box or casing 3 having a rising front 4 slanting toward the rear, and in which there is provided an opening 5 at an appropriate height and this opening is in part closed by a transparent plate 6 which may ordinarily be of clear glass. The glass plate 6 stops short of the lower edge of the opening 5 and said opening is there provided with a rounded edge 7 (see Fig. 4), with the curvature forwardly and downwardly.

Leading downwardly from a point a short distance above the rounded edge 7 and located on the outer face of the front of the casing is a chute 8, which may be a metal chute, extended to the table 1 where the chute opens through a passage 9 into a receptacle 10, the latter being shown as in the form of a drawer capable of being moved from the table in order that access may be had to the interior of the drawer.

Extending across the front of the casing 1, at a point close to but below the lower edge of the glass plate 6, is a rock shaft 11 carried by journal bearings 12 secured to the front of the casing and at one end projecting therebeyond and formed into a crank handle 13, which may be done by simply bending the shaft appropriately. Fast on the shaft 11 is a clamp strip 14 having two wings 15, 16 in acute angular relation, and near one end of the wing 16 there is provided a stop pin 17. The wing 15 is so situated as to normally underride the lower edge of the glass pane or plate 6, with the wing 16 in engagement with the front face of the glass pane close to its lower edge, being there held by a spring 18 secured at one end to the handle 13 and at the other end to one side of the box or casing 3.

Extending across the front of the casing and projecting through the opening 5 is a rockable shelf 19 mounted on trunnions 20 at the ends, said trunnions having jour-

nal supports 21 on the inner face of the front of the casing 3. The shelf 19 is connected at one end by a link 22 to a latch lever 23 carried by a bracket 24 secured to the inner face of the front of the casing. The rock lever 23 is attached to a spring 25, in turn attached to the bracket 24, so that the normal tendency of the lever 23 is to be held in an elevated position with the same 10 tendency transmitted to the shelf 19 by the link 22. The parts are so proportioned that the shelf 19, at its front edge, underrides the wing 16 of the clamp device 14, the wing serving as a stop for limiting upward movement of the shelf and holding the latter in proper position, and also serving to engage the lower edge of the glass plate for limiting rocking movement of the clamp into released position.

20 The lever 23 projects forwardly through a slot 26 in the front of the casing to one side of the chute 8, so that its front end is accessible from the front of the casing.

Secured by hinges 27 to a shelf 27^a across 25 the front of the casing near the lower end of the opening 5 is a presser board 28 similar to the presser boards customarily employed in photographic printing machines, and in common with other presser boards 30 the presser board 28 is provided with a fac- 29 ing 29 of felt or some other suitably soft material.

The presser board 28 carries at one side a pivoted finger 30 under the control of a 35 spring 31, constraining the finger in one direction about its pivot, but yielding to forces tending to move it in the other direction. The finger 30 is situated to engage the forward end of the rock lever 23 as the presser board is moved from pressing position to open position, but the finger 30, as 40 the lever 23 is pressed downwardly, ultimately escapes from the outer end of the lever 23 so that the latter will automatically 45 return to its first position. By providing a stop 32 or other appropriate means in the path of the finger 30, the presser board 28 may be supported in a position, when open, to provide a temporary table 50 for negatives or paper at a convenient downward slant.

Fast to and rising from the shelf 27^a, at opposite sides of the opening 5, are spring clips 33 designed to engage and hold a photographic negative 34, which, in the particular showing of the drawings, is indicated as a film which may include several negatives. It is customary to make prints from 55 films containing a suitable number of negatives without cutting the negatives, thus facilitating the handling of the films in the printing process. The film 34 is held across the glass plate 6 by the clips 33. In order to introduce the film 34 the clamp 14 is 60 brought to carry the wing 16 away from the

glass plate so that the lower edge of the film may be readily introduced between the wing 16 and the plate, after which the clamp 14 is released and the lower edge of the film is adjusted and clamped along its 70 lower edge against the glass plate, with the part of the film to be printed above the rounded edge 7 of the opening 5 where leading into the chute 8. If it be desired to provide the print with a blank border, a 75 mat or mask 35 is adjusted with respect to the negative, and the wing 16, forming the negative-engaging part of the clamp 14, may constitute the lower portion of the mat, the remainder of the mat completing the 80 border-forming part of the mat. The paper, indicated at 36, is then adjusted to the mat side of the negative, both the mat and paper being brought against the pin or stop 85 17 so that the parts are suitably adjusted. The lower edge of the paper rests upon the shelf 19 which, at the time, is in the raised or level position. Following these operations, the presser board 28 is raised by hand, or otherwise, to engage and hold the paper 90 36 against the mat 35 and over the negative.

During this time a constantly energized electric lamp 37 within the casing 3 furnishes light, whereby the negative mat, when used, and paper, may be properly adjusted. The constantly burning light is, of course, of non-actinic quality and may 95 ordinarily be an orange light, since sensitized paper of the type ordinarily employed for the purpose may be safely handled in 100 so-called orange light.

Within the casing 3 there is also located another electric light 38 having suitably high actinic qualities. The electric light 38 may be in the form of a single bulb or a 105 group of bulbs, depending upon circumstances, and in the case of a group of bulbs the arrangement is such as to spread the light as evenly as may be. One terminal of an electric circuit for energizing the lamp 110 38 is carried to the exterior of the casing, as indicated at 39, and is there in the path of an electric contact 40 on the presser board 28, so that when the board is moved to the closed position, the electric circuit is closed 115 between the terminals 39 and 40 as the presser board engages the paper 36, thus causing the production of actinic light within the casing to traverse the negative and affect the sensitized surface of the paper. 120 The printing of the paper, even with relatively dense negatives, requires but a short time and hence the presser board may be held by hand during the printing operation.

It is advantageous to number or otherwise mark each print of an order, the different orders having different numbers or marks so that at the end of a day's work there is no difficulty in separating the prints in accordance with the different orders. For 125 130

this purpose, a numbering device 41 is mounted on the presser board 28, so that each time the presser board is closed onto a side thereof. By providing the numbering device 41 with a handle 42, such handle may not only serve as a means for causing the imprinting of the number but the handle 42 may be utilized as a means whereby the board 28 may be actuated. When the board 28 is moved away from printing position, the electric light 38 is cut out of circuit by the separation of the terminals 39 and 40 and the presser board at the same time releases the paper sheet 36, which thereupon gravitates into the chute 8 and ultimately into the drawer 10. At the same time the finger 30 which, when the board 28 is in the closed position, is above the rock lever 23, engages the latter and moves it against the action of the spring 25, pulling down on the shelf 19 and permitting the print to drop to and through the chute 8. The mat or mask 35 may be held by the clamping wing 16 and will be so held so long as the handle 13 is not manipulated, this being due to the action of the spring 18. The operator, therefore, may make as many prints as desired of the negative by simply placing unexposed sheets of paper in position and closing the presser board 28 onto the placed sheet of paper. The exposure of the paper and disposition of the exposed paper are automatic. Consequently prints may be made with great rapidity and practically as rapidly as the necessary time of exposure will permit.

When it becomes desirable to change the negative, the lever 13 is manipulated, thus releasing the pressure of the clamp 14 upon the negative and in the case of a film containing several negatives the film may be adjusted to a new position and reclamped, the mat also being clamped if used. In order to facilitate the adjustment of the film it is advantageous to have the clamp 14 temporarily inactive and so there is provided a latch member 43 which may be fast to one side of the casing 3 adjacent to the lever 13 so as to hold the lever in a position where the clamp 14 is in the unclamped position.

What is claimed is:—

1. A photographic printing machine provided with a rearwardly slanting front having a light transmitting opening therethrough, light transmitting means at said opening, a rockable clamp member having two wings in acute angular relation, with one wing normally underriding the lower edge of the light transmitting means and the other wing in engagement with the front face of the light transmitting means close to its lower edge, a chute leading from the clamp plate downwardly, a rockable

shelf below the clamp plate and normally engaging the latter, and means connected to the shelf and accessible from the front of the machine for rocking the shelf. 2. A photographic printing machine provided with a rearwardly slanting front having a light transmitting opening therethrough, a glass plate at said opening, a rockable clamp strip having two wings in acute angular relation, with one wing normally underriding the lower edge of the glass plate, and the other wing in engagement with the front face of the glass plate close to its lower edge, a chute leading from the clamp plate downwardly, a rockable shelf below the clamp plate and normally engaging the latter, and means connected to the shelf and accessible from the front of the machine for rocking the shelf, a presser board for holding a negative against the glass plate, a spring controlled pivoted finger connected to the presser board, and a rock lever in position to be engaged by the finger with the lever and finger related to cause the finger to ultimately escape from the lever.

3. A photographic printing machine provided with an upwardly and rearwardly slanting front having an exposure opening therethrough, a hingedly mounted presser board movable toward and from the opening, a movable support for sensitized material, located at the front of the machine, and connections between the presser board and the movable support and operable by the presser board when it is swung away from the opening to discharge the sensitized material from the support.

4. A photographic printing machine provided with an upwardly and rearwardly slanting front having an exposure opening, a presser board movable toward and from the opening, a movable support, other than the presser board, for sensitized material, connections between the presser board and movable support for discharging the sensitized material when the presser board is moved away from the opening, and means whereby the support for the sensitized material is released to return to the supporting position before the opening movement of the presser board is completed.

5. A photographic printing machine provided with a casing having an upwardly and rearwardly slanting front with a light-transmitting portion, means for holding a photographic negative at the light-transmitting opening, a presser board movable toward and from the light-transmitting opening, a movable support at the light-transmitting opening for holding photo-sensitive material disposed against the negative, the sensitive material lying gravitationally against the negative irrespective of the clamping action of the presser board.

and connections between the presser board and the supporting means for the photo-sensitive material and including tripping means operable by the presser board when moved to partly open position to cause the photo-sensitive material to be automatically discharged by gravity.

6. A photographic printing machine comprising a casing with a light-transmitting opening, a presser board movable into and out of covering relation to said opening, means for holding a photographic negative at said opening, a tiltable shelf normally positioned with relation to the opening to support photo-sensitive material over the negative, and trip connections between the presser board and tiltable shelf and operable when the presser board has been moved to partly open position to tilt the shelf and discharge the photo-sensitive material by gravity from printing position.

7. A photographic printing machine provided with a casing having a light-transmitting opening therethrough with a glass cover plate, and a rockable clamp at the opening having angularly related wings radial to the axis of rocking, with one wing normally underriding one edge of the glass plate and engageable therewith to limit swinging movement of the clamp into released position, and with the other wing directed toward the face of the glass plate or a negative held against the glass plate by the clamp, said clamp having a normal tendency toward the clamping position, and means for holding the clamp in open position against its normal tendency.

8. A photographic printing machine provided with a casing having a light-transmitting opening therethrough with a glass cover plate, a chute below the level of the glass plate, a movable shelf above the chute for supporting sensitized material, and a clamp between the lower edge of the glass plate and the shelf and extending across the opening, said clamp being mounted to rock and having a clamping wing for engaging a negative and having a second wing engageable by the shelf for limiting movement thereof in one direction, a manipulating device to hold the clamp in the open position, and means for imparting a normal tendency to the clamp to move toward the closed position.

9. A photographic printing machine hav-

ing an upwardly and rearwardly slanting front with a light-transmitting opening therethrough, means for securing a photographic negative at the light-transmitting front, a presser board movable toward and from the opening through the front of the casing, a tiltable shelf for supporting a photo-sensitive sheet in operative relation to a negative, and trip connections between the presser board and the tiltable shelf whereby to tilt the presser board to discharge a photo-sensitive sheet thereon when the presser board is moved toward the open position.

10. A photographic printing machine having an upwardly and rearwardly slanting front with a light-transmitting opening therethrough, means for securing a photographic negative at the light-transmitting front, a presser board movable toward and from the opening through the front of the casing, a tiltable shelf for supporting a photo-sensitive sheet in operative relation to a negative, and trip connections between the presser board and the tiltable shelf whereby to tilt the presser board to discharge a photo-sensitive sheet thereon when the presser board is moved toward the open position, said connections comprising a rock lever connected to the tiltable shelf, and a pivoted finger connected to the presser board and movable into and out of engagement with the lever on progressive movement of the presser board toward the open position.

11. In a photographic printing device a casing having a light transmitting opening therethrough, a glass plate adapted to cover the opening, a rockable clamp adjacent said opening and having angularly related wings radial to the rocking axis, with one wing normally underriding one edge of the glass plate, the other wing engageable with a negative to clamp it against the face of the plate, and a support for holding a sheet of photo-sensitive material inclined against the negative, said clamp having a stop thereon for determining the position of the photo-sensitive sheet with relation to the negative.

In testimony, that I claim the foregoing as my own, I have hereto affixed my signature.

CLEVELAND SIMPSON.
